FIG. 1

FIG. 6

FIG. 2

FIG. 3

FIG. 4

FIG. 5

FIG. 7

FIGURE 1 is a perspective view of an artificial upper cuspid tooth showing my new design;

FIGURE 2 is a rear (lingual) elevational view thereof;

FIGURE 3 is a front (buccal) elevational view thereof;

FIGURE 4 is a side elevational view of the right side (mesial) of FIGURE 3;

FIGURE 5 is a side elevational view of the left side (distal) of FIGURE 3;

FIGURE 6 is a top plan view thereof; and

FIGURE 7 is a bottom (occlusal) plan view thereof.

The characteristic feature of my design resides in the specific configuration of the occlusal table of the upper cuspid tooth, as best illustrated in FIGURE 2 of the drawing.

I claim:

The ornamental design for an artificial upper cuspid tooth, substantially as shown and described.
